TABLE

Russel Wright, New York, N. Y., assignor to Shwayder Brothers, Ecorse, Mich., a corporation of Colorado

Application February 24, 1955, Serial No. 34,661

Term of patent 14 years

(Cl. D33—14)

Fig. 2

Fig. 1 is a perspective view of a table showing my new design; and

Fig. 2 is a fragmentary side elevational view thereof, on a reduced scale.

The side not shown is the same in appearance as the side shown in Figs. 1 and 2.

I claim:

The ornamental design for a table, substantially as shown and described.
